UNITED STATES PATENT OFFICE.

MOSES R. TURNER, ROBERT G. KIRBY, AND JOHN R. TURNER, OF ADAMS, INDIANA, ASSIGNORS TO CHARLES L. WHITE, OF DECATUR COUNTY, INDIANA.

PUMP.

SPECIFICATION forming part of Letters Patent No. 563,992, dated July 14, 1896.

Application filed January 6, 1896. Serial No. 574,438. (No model.)

To all whom it may concern:

Be it known that we, MOSES R. TURNER, ROBERT G. KIRBY, and JOHN R. TURNER, citizens of the United States, residing at 5 Adams, in the county of Decatur and State of Indiana, have invented certain new and useful Improvements in Pumps; and we do declare the following to be a full, clear, and exact description of the invention, such as 10 will enable others skilled in the art to which it appertains to make and use the same, reference being had to the accompanying drawings, and to the letters of reference marked thereon, which form a part of this specification. 15

Our invention relates to that class of pumps which are adapted to be used when submerged; and it consists of certain new and novel features of construction whereby our pump is 20 adapted for use in driven wells from which water or liquids may be pumped with a minimum amount of power, and discharge a continuous flow without harming or damaging effects to the mechanism, as will be more 25 fully described hereinafter.

The object of our invention is to provide an improved pump which is suitable for raising water to considerable heights, which may be used either above or below the liquid, and 30 which combines an air-chamber, the whole capable of being lowered and used as a submerged pump in deep driven wells of small diameter; and with these objects in view we have constructed our pump of few parts and 35 simple design, which is cheaply manufactured and is reliable and durable in use.

Referring to the drawings, Figure 1 represents a vertical sectional view having the air-chamber and piston-rods broken above the 40 cylinder. Fig. 2 is a cross-sectional view on the line X X, showing the valve-openings in the ends of the cage. Fig. 3 is a vertical side view of the valve-cage.

In the drawings, A represents the pump-cylinder, having smooth inner surfaces, preferably constructed of tubing, to which is attached at the lower end the cap U, having the check-valve T; and at the upper end of the cylinder is attached the cap or head D, having 45 a hole in the center provided with screw-

threads, into which is screwed the air-chamber B. At the top of this air-chamber is coupled a pipe for conveying the water to the top of well, at the upper end of the pipe there being a discharge-spout C and packing-nut F 55 to prevent splashing of the water. A suitable fulcrum H is attached to lug H', to which is connected an operating-lever G, or any other suitable means may be used. At the upper part of the cylinder are openings K', having 60 valve-seats at the inner side of the cylinder, which are covered by check-valves K, and when desired to use the pump above water suitable pipes may be attached at these valve-openings and at the opening at bottom of cylinder and extend down into the water. 65

The particularly novel features of our pump are the double piston or plunger, comprising the upper plate M and the lower plate M', which have the water-passages L L'. The 70 lower plate is secured, by means of screw-threads and the check-nut I', to the pump-rod I. A valve-cage P, having apertures R in its sides, is screwed to both the lower and upper plates of the piston, thus connecting 75 the upper plate, by means of the lower one, to the actuating pump-rod. To the upper plate of the piston is screwed a hollow plunger or sleeve W of such length that when the plunger is at the bottom end of its stroke the 80 hollow sleeve will protrude through the upper cap of the cylinder into the air-chamber. The hollow plunger, where it passes through the upper cylinder-cap, is provided with a leather packing J', held in place against the cap by 85 a plate J, secured by suitable screws, which packing allows the plunger to move longitudinally without leaking.

S is a floating valve movable in the cage P and guided thereby. This valve has an upper plate S' and the lower plate S'', the two being connected integrally by the sleeve S', and a hole through the center of the plates and the sleeve S' serves as a water-passage through the valve. 90

At the upper end of the double-headed piston is a leather packing N, and between it and the cage P is a washer O, so that when the cage is screwed onto the plate M the consequent rotary motion of the cage may not 95 100

abrade the leather, but will slide against the washer. The lower plate M' is likewise provided with a packing N' and the washer O'.

In practical operation, the piston and plunger being at the upper end of its stroke, as in Fig. 1, and about to descend, the valve S will rise and seat against the upper plate of the piston, opening the waterways L' in the lower plate, admitting water through the same, and simultaneously closing the openings L in upper plate, thus making the upper plate a suction-valve. As the plunger descends the liquid contained in the lower portion of the cylinder is forced upward by the pressure of the plunger, and passes through the center of the valve, through the passage W in the hollow plunger, and is discharged through the passage E in the air-chamber and upward to the opening provided.

While this action is taking place the upper end of the cylinder is having liquid drawn in through the upper valves K, when the piston is ready to return on its upward stroke. As it begins this movement the floating valve is seated against the lower head of piston, covering the openings L', thus transforming this lower head into a suction-valve, which in its stroke will draw liquid into the lower end of the cylinder through the bottom check-valve, and the liquid in the upper end of the cylinder is forced through the openings L into and around the cage, thence through the passage W of the hollow plunger, and outward through the air-chamber and passage E, as in the other stroke, the action being completed as shown in Fig. 1.

It is obvious that many minor changes in the details of construction may be used, and various forms of check-valves may be applied, which being old are not claimed, the essential novelty of our invention being the double-headed piston having the internal floating valve, the connected hollow plunger, and adjacent air-chamber, which together effect a valuable improvement in pumps of this class.

Having described our invention, what we claim, and desire to secure by Letters Patent of the United States, is—

1. In a pump for raising or forcing liquids having a tubular cylinder; the combination with the cylinder, having a suitable check-valve at each end of same; of a double-headed valve-piston having apertures in each head attached at its lower end to an actuating-rod passing upward through the top of said cylinder to a suitable lever or motor for operating same; a hollow plunger or sleeve connected so as to be water-tight to the upper head of said piston, said hollow plunger being slidable vertically through the upper cap or head of said cylinder, through which plunger the said actuating pump-rod passes and around which and the walls of said hollow plunger is provided a waterway for discharging liquids; a suitable packing attached to the upper cylinder-head, and around said

hollow plunger, by which the same is rendered water-tight when making its upward stroke; a floating valve inclosed between the two heads of said double-headed piston covering apertures in either head, guided by means of a connecting valve-cage which forms and is an essential part of said double-headed piston, being its connecting-body; an air-chamber attached to the upper head of said cylinder, and a discharge-pipe connected to the upper part of said air-chamber, substantially as and for the purpose shown and described.

2. In a pump, the combination of a cylinder having a suitable check-valve at the bottom thereof and provided with the check-valves situated at the side walls near the upper end thereof; the valve-piston consisting of the two perforated packed heads, the cage connecting said heads and the valve working in said cage; the hollow plunger attached rigidly at its lower end to the upper one of said piston-heads, the upper end of said plunger passing through a packed aperture in the upper cylinder-head and terminating in a suitable air-chamber; and the pump-rod attached at its lower end to the lower one of said piston-heads and passing through said hollow plunger and said air-chamber to connect with a suitable operating device, substantially as and for the purposes shown and described.

3. In a pump, the combination of the cylinder provided with the check-valves at each end, the double-headed valve-piston working therein, the hollow plunger attached to the upper head of said piston, the pump-rod connecting the lower head of said piston, the air-chamber connected to the upper head of said cylinder and having the discharge-spout and packing at the upper part, the said pump-rod passing through said hollow plunger, said air-chamber and said packing, the leather packing at the inner side of the upper cylinder-cap around said hollow plunger, and suitable means by which said pump-rod may be operated, substantially as shown and described.

4. In a pump, the combination of the cylinder, the double-headed piston having its lower head attached to an actuating pump-rod, a skeleton cage connecting the two heads of said piston, said heads having the apertures therethrough, the vertically-movable valve inclosed between said piston-heads within said cage and having seats at each end capable of seating and alternately covering the said apertures in each of said heads, the vertical hollow plunger or tube attached at one end to the upper head of said piston and passing through a packed central opening in the upper head of said cylinder, and suitable means for operating said pump-rod, substantially as shown and described.

5. In a pump of the kind described, the combination of the cylinder; the check-valves at each end thereof; the head or cap D; the air-chamber B, arranged as shown; the piston having the heads or plates M M' provided

with the water-passages L L'; the packings N N'; the washers O O'; the cage P connecting said heads; the valve S working in said cage; the plunger W attached to said head M; the 5 packing J' secured by the plate J; the pump-rod I attached to said head M', and means substantially as described whereby said pump-rod may be operated, for the purposes set forth.

In testimony whereof we affix our signatures in presence of two witnesses.
